CLAIM

The ornamental design for a reagent container or the
like, as shown and described.

DESCRIPTION

FIG. 1 is a front perspective view of a reagent container
or the like showing our new design;

FIG. 2 is a rear perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is a bottom plan view thereof;

FIG. 9 is a sectional view along line 9—9 of FIG. 7; and
FIG. 10 is a top perspective view thereof, with the
broken line showing for illustrative purposes only and
forming no part of the claimed design.

FIG. 1

FIG. 2

FIG. 3

FIG. 4

FIG. 5

FIG. 6

FIG. 7

FIG. 8

FIG. 9

FIG. 10
